UNITED STATES PATENT OFFICE.

FREDERICK D. ANDERSON, OF DENVER, COLORADO, ASSIGNOR TO NSCO COMPANY,
OF BINGHAMTON, NEW YORK, A CORPORATION OF NEW YORK.

LEVELING DEVICE FOR PHOTOGRAPHIC CAMERAS.

1,167,967.

Specification of Letters Patent. Patented Jan. 11, 1916.

Application filed August 25, 1915. Serial No. 47,330.

To all whom it may concern:

Be it known that I, FREDERICK D. ANDERSON, a citizen of the United States, and a resident of the city and county of Denver and State of Colorado, have invented a new and useful Leveling Device for Photographic Cameras, of which the following is a specification.

It is the purpose of this invention to provide a device whereby a photographer, whether skilled or not, may quickly, accurately and easily level his camera at the time of an exposure. The device is universal in its leveling action, inexpensive and so simple in its construction and method of operation, that it will maintain its serviceability indefinitely, which is not the case with the liquid levels now usually employed, for they are liable to fracture, and owing to evaporation, or other escape of their liquid, in time become inoperative.

Broadly stated, my new leveling device acts upon the principle of a gravity acting plumb bob.

In the drawings hereof, Figure 1 is a sidewise elevation of a finder embodying the invention, the hood being elevated; Fig. 2 is a sidewise view similar to Fig. 1, the hood and co-acting parts being shown in section, the body of the finder being in elevation; Fig. 3 is a front view similar to Fig. 1, showing the parts in the position they occupy when the camera is properly leveled; Fig. 4 is a plan view on the line 4—4 of Fig. 3, looking in the direction of the arrow; Fig. 5 is a horizontal sectional view taken on the line 5—5 of Fig. 3.

In the drawings 1 represents the body of the finder supported in the instance shown upon a bracket or standard 2.

3 is the finder lens casing, 4 (see Fig. 2) the mirror, 5 the observation plate, 6 the hood, which is pivoted at 7, 7, to the body 1 in any preferred manner. The hood, which I prefer to make of metal, comprises two side pieces 8, 8, and a back 9, and in the back is preferably made a closed recess 10, which may be and preferably is formed by stamping a projection in the metal of the hood. I prefer to supply the recess with an opening 11 (see Figs. 2 and 5) covering which is a glass plate 12 secured in any preferred manner. The opening in the back of the recess 10 and the interior glass plate are not essential because the rear wall or the

upper wall of the recess, depending upon whether the hood is closed or open, may be solid, if preferred.

13 is a piece of metal preferably, but not necessarily triangular in shape, which is pivoted at 14 to the upper part of the closed back of the hood. The engagement or bearing of the triangular piece 13 upon the pivot 14 is exceedingly loose, so that the triangular piece will instantly respond under the action of gravity, to any divergence from a horizontal position of the camera, so that a pointer 15, which may beneficially be formed on the lower edge of the triangle, co-acting with a fixed mark or index 16 on the inside of the hood (see Fig. 3), will at once indicate whether the camera is truly level or there be any divergence therefrom.

In order that the back of the hood when it is elevated may be as nearly as possible in a truly vertical line, it is provided at its lower edge with a flange 16^a (see Figs. 2 and 4) which resting against the adjacent surface of the finder proper, acts as a stop to determine the degree at which the finder may be opened.

It will be noted that the action of the parts as thus far explained resembles that of a gravity acting plumb bob and that it indicates whether or not the camera is level, but only in a right and left direction, although this same device will also, with all needful accuracy, in most cases, indicate whether the camera is level forwardly and rearwardly, and this result will be aided by providing upon the flange 16 of the hood a horizontally extending indicator (see Fig. 4) 17, with the forward end of which the point 15 on the triangular swinging part 13 may be made to register. In order, however, that the forward and rearward leveling of the camera may be secured with greater exactness I prefer to cut out from the center of the triangular piece 13, a separate or supplemental plumb bob 18 (see Figs. 3 and 5) which is pivoted, as at 19, to the part 13 in such manner that its oscillations shall be forwardly and rearwardly, whereas the oscillations of the part 13 are, as stated above, to the right and left, and the construction is such that when the surface of the supplemental plumb bob 18 is flush or coincident with the surface of the part 13, which may be readily ascertained by observing the adjacent edges of these two

parts, then the camera will be level front and rear, so that the combination of these two instruments, the right and left swinging plumb bob and the forwardly and rearwardly swinging supplemental plumb bob, will secure the accurate leveling of the camera in all directions, the device operating as a universally acting level.

In order that the two swinging plumb bobs may not interfere with the forward closing of the hood of the finder, I make the engagement between the plumb bob 13 proper and the pivot 14 such that although the plumb bob may freely swing without any friction or binding whatever to right and left, its movements forwardly and rearwardly will be limited so that when the hood is tipped forwardly and downwardly, the plumb bob will not so change its position as to interfere, and in order that the supplemental plumb bob 18 may be similarly limited in its movements, I provide it with two little laterally extending wings or fingers 19^a (see Figs. 3 and 5) which are set so far to the rear as not to interfere with the desired movements of the supplemental part but will prevent its too great forward swing.

It will be understood by those who are familiar with such matters that various changes may be made in the details of construction and method of combining the parts, that is to say, as suggested above, it is unnecessary that there shall be any glass plate in the recess 10 made in the hood, but I prefer that construction because thereby the plumb bobs are somewhat illuminated and their action more readily observed; also it is not absolutely necessary that there shall be any recess whatever. All that is necessary will be to offset the main plumb bob from the back of the hood sufficiently to permit the desired swinging movements of the parts. Also obviously the shape of the plumb bob, or the plumb bobs, if more than one be used, may be such as preferred, and the special method of their pivoting to the adjacent parts may be varied and a single plumb bob, if desired, may be employed, and obviously its shape and special con-

struction may be such as preferred. Furthermore, a gravity acting device similar to or performing the same function as the plumb bobs referred to need not necessarily be inclosed within the hood, but it is especially advantageous to have them located there and that feature forms an important but not an essential part of my invention, because if so, when the finder is not in use and the hood closed down, these parts, which are necessarily somewhat delicate in their construction, are housed within and protected against injury by the hood, and also during the finding operation they will, if located within the hood, be in the most convenient place for convenient observation by the operator in conjunction with the finding of the image upon the observation glass 5.

I claim:

1. In a finder a gravity acting camera leveling device pivotally connected to the interior of the hood of the finder.
2. In a finder a gravity acting camera leveling device so pivotally connected to the hood of the finder that it will afford no obstruction to the closing of the hood.
3. In a finder a hood provided with a stop to determine the extent to which the hood may be opened and a gravity acting camera leveling device pivoted near the swinging edge of the hood.
4. In a finder, a hood, a primary gravity acting camera leveling device pivotally connected to the hood and adapted to right and left oscillation and a supplemental gravity acting camera leveling device pivotally connected to the primary leveling device and adapted to forward and rearward oscillation.
5. In a finder, a hood having a recess in its back, a primary gravity acting camera leveling device pivoted to the hood in front of the recess and adapted to right and left oscillation and a supplemental gravity acting camera leveling device pivoted to the primary leveling device and adapted to forward and rearward oscillation.

In testimony whereof I have signed my name to this specification.

FREDERICK D. ANDERSON.
